(57) **CLAIM**

The ornamental design for swimming goggles, as shown and described.

DESCRIPTION

FIG. 1 is a perspective view of the swimming goggles of the present invention;

FIG. 2 is a front elevation view thereof;

FIG. 3 is a rear elevation view thereof;

FIG. 4 is a top plan view thereof, the bottom plan view being a mirror image thereof;

FIG. 5 is a right side elevation view thereof; the left side elevation view being a mirror image thereof;

FIG. 6 is a section view thereof taken along line A-A of FIG. 2;

FIG. 7 is a section view thereof taken along line B-B of FIG. 4;

FIG. 8 is a section view taken thereof along line C-C of FIG. 4; and,

FIG. 9 is a perspective view of the swimming goggles with a belt attached thereto.

The broken lines in the figures represent environmental structure and form no part of the claimed invention.
